EXPLOSIVE

Glenn A. Pritchett and Herbert G. Walker, Reno,
Nev., assignors to Monite Explosives, Inc.,
Reno, Nev., a Corporation of Nevada

No Drawing. Application August 14, 1931
Serial No. 557,382

10 Claims. (Cl. 52—8)

Our invention relates to free-flowing explosives and has for its objects a process for producing a free flowing high powered explosive powder which will be possessed of high safety factors against accidental setting off from friction, heat, or ordinary percussion. A more particular object of our invention is to produce a powder of the above characteristics from explosive ingredients including a chlorate base. A further object of our invention is the product of our process, or an explosive powder having the characteristics herein set forth.

Before describing our invention it may be stated that numerous inventors have produced free flowing explosive powder, ordinary glazed black powder, for example, being such a powder, but this, as is well known, is relatively weak in blasting strength and at the same time relatively dangerous since it may easily be set off by friction or heat. Other powders have been made combining the more powerful explosives in their combination, but in so far as can be learned such free flowing powders have not been made from ingredients including a chlorate base, probably owing to the sensitive nature of sodium chlorate which heretofore made it impossible to control such powders.

However, since the inclusion of chlorate makes it possible to produce a powder of a strength running up to 60% or more equivalents to nitro-glycerine dynamite, we worked to overcome the generally hazardous nature of powders incorporating this material while retaining the value of this superior explosive agent, and have produced a powder of better free flowing qualities than any powder on the market except black powder, yet with safety features greatly exceeding any commercial explosive powders obtainable.

40 Our invention comprises the use of certain ingredients, heat-treated to reduce their water content, specially sized particles, carrying within their interstices a percentage of dinitrotoluol, and finally glazed with an organic glazing material, the varying strengths of the powder being secured by changing the percentage of sodium chlorate used. The final result being a free flowing powder of high explosive value which cannot be set off by direct contact with burning matches, ignited 50 gasoline soaked rags, or such friction and/or percussion as would at once set off most any powder known, yet withal a powder which may be even more readily exploded by means of a fulminate cap or electrical exploder than low 55 strength bulb powders obtainable.

The preferred combination of ingredients comprising our improved explosive are: sodium chlorate, sodium nitrate, wood flour (cottonwood), dinitrotoluol, carbonate of lime, and lycopodium powder, though in some cases nitronaphthalene and nitro-benzol may be incorporated, and instead of cottonwood flour, bagasse flour has been found useful.

Preparation of materials

1. The crystalline or salt ingredients are dried out to a moisture content preferably not exceeding four-tenths of one per cent (0.4%).

2. The wood flour is dried to a moisture content preferably not exceeding one per cent.

3. The dinitrotoluene is heated to a temperature preferably not below 120° F. at time of introduction to the mixture, and it should be of a melting point lying between 35 and 45° C.

4. The crystalline or salt ingredients are heated to a temperature preferably not below 105° F. at time of mixing. To secure the full advantages of our invention it is also necessary that the salts used be of certain sizes, as follows:

The sodium nitrate is crushed through rolls so adjusted as to produce the maximum percentage of grains lying between 8 and 18 mesh, and this is preferably then classified by screening and selection is made of such particles as will pass an 8 mesh screen and will not pass an 18 mesh screen.

The sodium chlorate is similarly classified to retain particles lying between 50 and 100 mesh.

The melted liquid dinitrotoluene is introduced to a mixture of the other ingredients mentioned (omitting the lycopodium powder) in percentages of from about 5% to 15% in any suitable mixing apparatus in a manner to give the most intimate contact of particles to induce the greatest possible absorption of the oil.

After thoroughly incorporating the dinitrotoluene, the mass is re-screened through a ten mesh screen to break up any agglutinated particles, and the grains are thereafter glazed by tumbling in a barrel with about 2% of lycopodium powder.

Formula

It is possible to entirely omit the chlorate salt and obtain a 5% strength powder by using the following ingredients:

	Per cent
Sodium nitrate	about 85
Dinitrotoluol	10
Wood flour	5
Carbonate of lime	1

While a 40% strength powder would contain:

	Per cent
Sodium chlorate	30
Sodium nitrate	55
5 Dinitrotoluol	10
Wood flour	5
Carbonate of lime	1

Other strengths of powder below 40% or up to 10 60% or more are produced by changing the relative amount of chlorate to nitrate, increasing the chlorate and reducing the nitrate in substantially equal amounts, the 60% powder would contain 60% chlorate and 25% nitrate.

15

The product

a—The resulting powder is thoroughly non-plastic so that it is free flowing to an unusual degree so as to pass readily into small bore holes.

20 b—It is very resistant to moisture.

c—It has an average specific gravity of about 1.642 relative to silica sand of 20/30 screen fineness taken at 1.00 and is therefore from 6% to 25 9% denser than most standard brands of free flowing powder available on the market so that a given weight will occupy less space, or conversely, a given bulk has greater explosive energy.

d—It is free from any tendency to separate 30 its liquid from other ingredients.

e—Is perfectly stable under extreme variations of temperature.

f—Cannot be set off by direct contact with 35 burning matches or cigarettes. A test of burning a whole box of Domino matches on top of a pile of 500 grams of powder, or pouring the powder on the burning matches failed to ignite it. It could not be ignited from a burning fuse.

A gasoline soaked rag placed on a pile of the 40 powder and ignited only fused the top layer to a crust, and upon removal of the crust the lower layer was found to shoot as well as before.

g—Standard friction tests made on U.S. Government Bureau of Explosives type friction pendulum with fibre shoe on steel anvil, gave no failures in ten trials. Ten further trials with steel shoe were made with no failures though this test was one no high explosive of this type would pass. An extra severe test was made, 8 or 10, wherein 45 7% of sand was mixed with the charge of explosive, thus inducing the greatest possible friction and with steel upon steel, but no failures resulted from the test.

In developing our invention we have discovered 50 that it is necessary in order to produce a stable and reliable product that the dinitrotoluol used should have a melting point lying substantially between 35 and 45° centigrade, and that the fractions above and below this range should be eliminated, and that lack of this knowledge was one of the causes of failure in earlier attempts to produce a powder of this nature.

We have also found, that while instead of the 55 sodium salts, the corresponding potassium and ammonium salts, may in some instances be used, the resulting explosive is lacking in several of the advantages found in our product.

From the above description of our invention it 60 will be seen that we have produced a high powered explosive of great stability and having remarkable safety attributes, and from a base here-

tofore generally considered unreliable. We therefore feel entitled to claims commensurate with the importance of our contribution to the art and accordingly we claim:

1. An explosive powder in granular form containing dinitrotoluol and sodium chlorate and with the individual grains of the powder glazed exteriorly with lycopodium powder. 80

2. The process of making an explosive powder of sodium nitrate, dinitrotoluol and cellulose flour, which comprises reducing the water content of the nitrate to less than one-half of one per cent, and heating the dinitrotoluol to a temperature above 115 degrees F. before mixing the same. 85

3. The process of making an explosive powder of sodium nitrate, dinitrotoluol and cellulose flour, which comprises reducing the water content of the nitrate to less than one-half of one per cent, reducing the water content of the cellulose flour to below 1 1/4%, and heating the dinitrotoluol to a temperature above 115 degrees F. before mixing the same. 90

4. The process specified in claim 2 plus wherein the nitrate has been classified into grains lying substantially between 8 and 18 mesh. 100

5. The process of making an explosive powder which comprises substantially drying sodium nitrate and sodium chlorate, granulating and classifying the salts to bring the nitrate substantially between 8 and 18 mesh, and the chlorate between 50 and 100 mesh, incorporating therewith a quantity of organic flour and dinitrotoluol, and granulating the mass. 105

6. The process of making an explosive powder which comprises substantially drying sodium nitrate and sodium chlorate, granulating and classifying the salts to bring the nitrate substantially between 8 and 18 mesh, and the chlorate between 50 and 100 mesh, incorporating therewith a quantity of organic flour and dinitrotoluol and an alkali. 110

7. The process of making an explosive powder which comprises substantially drying sodium nitrate and sodium chlorate, granulating and classifying the salts to bring the nitrate substantially between 8 and 18 mesh, and the chlorate between 50 and 100 mesh, incorporating therewith a quantity of organic flour and dinitrotoluol, granulating the mass and glazing the grains exteriorly. 120

8. The process of making an explosive powder which comprises substantially drying sodium nitrate and sodium chlorate, granulating and classifying the salts to bring the nitrate substantially between 8 and 18 mesh, and the chlorate between 50 and 100 mesh, incorporating therewith a quantity of organic flour and dinitrotoluol, granulating the mass and glazing the grains exteriorly with lycopodium powder. 125

9. A free flowing explosive powder comprising sodium chlorate with particles substantially all graded in size between 50 to 100 mesh, sodium nitrate graded in size of particles substantially all between 8 to 18 mesh, bound together with dinitrotoluol hard at ordinary temperatures. 130

10. A free flowing explosive powder containing sodium chlorate with particles substantially all graded in size between 50 to 100 mesh, and dinitrotoluol of a grade hard at ordinary temperatures. 140
